DESIGN FOR A DRESS OR SIMILAR ARTICLE

Herman Beispel, New York, N. Y.

Application February 10, 1941, Serial No. 98,881

Term of patent 3½ years

To all whom it may concern:

Be it known that I, Herman Beispel, a citizen of the United States, residing in the city, county, and State of New York, have invented a new, original, and ornamental Design for a Dress or Similar Article, of which the following is a specification, reference being had to the accompanying drawing, forming part thereof.

Fig. 1 is a front view of a dress showing my design;

Fig. 2 is a rear view of the dress shown in Fig. 1;

Fig. 3 is an enlarged fragmentary view of the upper front portion of the dress shown in Fig. 1,

illustrating the open-work embroidery thereon in detail.

The characteristic feature of my design resides in the combination on the dress disclosed of the specific embroidery on the upper front portion, in association with the harmonizing embroidery about the cuffs, and an insert of contrasting material along the front portion of the skirt and about the neckline, all as shown.

I claim:

The ornamental design for a dress or similar article, as shown and described.

HERMAN BEISPEL.
